US00D999956S

(12) **United States Design Patent** (10) **Patent No.:** **US D999,956 S**
(45) **Date of Patent:** **** Sep. 26, 2023**

(54) **DESK LAMP WITH WIRELESS CHARGING STAND**

(71) Applicant: **Guangzhou Cefong Technology Co., Ltd.**, Guangzhou (CN)

(72) Inventor: **Congbing Wang**, Guangzhou (CN)

(**) Term: **15 Years**

(21) Appl. No.: **29/846,887**

(22) Filed: **Jul. 20, 2022**

(51) LOC (14) Cl. **26-05**

(52) U.S. Cl.

USPC **D26/51**; D26/107

(57) **CLAIM**

The ornamental design for a desk lamp with wireless charging stand, as shown and described.

DESCRIPTION

FIG. 1 is a perspective view of a desk lamp with wireless charging stand showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an exploded view of the desk lamp with wireless charging stand, showing the wireless charging stand in an alternate configuration;

FIG. 10 is an enlarged detail view of a portion indicated with the number 10 in FIG. 2.

FIG. 11 is an enlarged detail view of a portion indicated with the number 11 in FIG. 5; and,

FIG. 12 is an enlarged detail view of a portion indicated with the number 12 in FIG. 8.

The dash-dash broken lines in the drawings depict portions of the desk lamp with wireless charging stand that form no part of the claimed design. The dot-dash broken lines in the drawings denote the boundaries of the enlarged detail views and form no part of the claimed design.

1 Claim, 12 Drawing Sheets
